UNITED STATES PATENT OFFICE.

FRANK B. SHAW, OF CALEDONIA, MICHIGAN, ASSIGNOR OF ONE-HALF TO CLYDE C. PIERSON, OF WAYLAND, MICHIGAN.

AIR PUMP.

Application filed August 25, 1922. Serial No. 584,228.

To all whom it may concern:

Be it known that I, FRANK B. SHAW, a citizen of the United States, residing at Caledonia, Kent County, Michigan, have invented certain new and useful Improvements in Air Pumps, of which the following is a specification.

This invention relates to improvements in air pumps.

10 The main object of this invention is to provide an improved air pump in which all of the parts are metal so that they are not affected by dryness or lubricant and, therefore, does not become inoperative.

15 Further objects, and objects pertaining to details and economies of construction and operation will definitely appear from the detailed description to follow.

I accomplish the objects of my invention 20 by the devices and means described in the following specification. The invention is clearly defined and pointed out in the claims.

A structure which is a preferred embodiment of the invention is clearly illustrated 25 in the accompanying drawing forming a part of this specification, in which:

Fig. I is a side elevation of my improved pump, a portion of the cylinder being broken away.

Fig. II is a vertical section on a line corresponding to line 2—2 of Fig. I, the parts being shown in full lines for convenience in illustration.

35 Figure III is a detail vertical section on a line corresponding to line 3—3 of Fig. II.

In the drawing the sectional views are taken looking in the direction of the little arrows at the ends of the section lines and 40 similar numerals of reference refer to similar parts throughout the several views.

Referring to the drawing, I provide a base 1 having foot extensions 2 at opposite sides and a discharge 3. The cylinder 4 is 45 preferably a piece of drawn tubing suitably secured to the base and is provided with a head 5 having an air inlet opening 6. The metallic piston 7 is provided with a plurality of annular piston ring grooves 8 for the 50 resilient metal piston rings 9, these rings being preferably provided with lap joints 10. The piston has a recess 11 at its lower end

and a central longitudinal bore 12 shouldered at its lower end to provide the valve seat 13.

55 The passage 14 leads from the top of the piston to the bore 12. The disk valve 15 is also of metal and is provided with a stem 16 engaging an opening 17 in the strap-like valve support 18 which is secured within the recess 11 by the screws 19. The weight of the valve holds it normally in open position by the pressure of the air on the down stroke causing it to seat.

60 The piston rod 21 is threaded into the piston and secured therein by the pin 20. The piston rod reciprocates to an opening 22 in the head and is guided thereby.

65 My improved air pump is especially designed by me as a tire pump and I have 70 shown the same as embodied for such use. The parts being all formed of metal are not liable to become inoperative as is the case with leather or fabric plungers or valves on account of drying out or rotting occasioned 75 by lubricant.

Having thus described my invention what I claim as new and desire to secure by Letters Patent is:

1. A structure of the class described comprising a cylindrical metal piston provided with a piston ring and having a recess in its lower end with a central bore extending therefrom and shouldered to provide a downwardly facing valve seat, there being 80 a passage leading from the upper end of said piston to said bore, a metal disk valve having a downwardly projecting stem, and a strap-like valve holder secured within said recess across said valve seat and having 85 a guide opening for said stem.

2. A structure of the class described comprising a cylindrical metal piston provided with a piston ring and having a longitudinal air passage with a valve seat at its 90 lower end, said piston being recessed around said valve seat, a metal disk valve coacting with said seat and having a downwardly projecting stem, and a valve holder disposed in said recess to extend across said seat and 95 having a guide opening therein for said stem.

3. A structure of the class described comprising a cylindrical metal piston having a

recess in its lower end and a central bore extending therefrom and shouldered to provide a downwardly facing valve seat, there being a passage leading from the upper end 5 of said piston to said bore, a metal disk valve having a central downwardly projecting stem, a strap-like valve holder secured

within said recess across said valve seat and having a guide opening for said stem, and a piston rod threaded centrally into the upper 10 end of said piston.

In witness whereof, I have hereunto set my hand and seal.

FRANK B. SHAW. [L. S.]
